UNITED STATES PATENT OFFICE.

ARTHUR C. EASTWOOD, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC CONTROLLER.

1,040,292.

Specification of Letters Patent.

Patented Oct. 8, 1912.

Application filed September 24, 1910, Serial No. 588,577. Renewed July 15, 1912. Serial No. 709,575.

To all whom it may concern:

Be it known that I, ARTHUR C. EASTWOOD, a citizen of the United States, residing at Cleveland, in the county of Cuyahoga and State of Ohio, have invented new and useful Improvements in Electric Controllers, of which the following is a specification.

My invention relates to electric controllers of that type in which a series of individually operated switches are employed in controlling the flow of current in an electric circuit or circuits. In controllers of this type, to carry out a given scheme of control, it is necessary, or at least advisable, to provide means for compelling the various switches to close in an invariable sequence to carry out the scheme of control for which the controller is specifically designed.

My invention relates particularly to means for compelling such invariable sequence in the closure of a series of independently operated switches.

My invention, in addition to making the closure of one switch depend upon the closure of a switch which precedes it in normal operation, goes further than this and provides means whereby the succeeding switch cannot close not only till the preceding switch has closed, but till the circuit controlled by the preceding switch has closed. This I consider a point of material improvement over controllers in which the closure of one switch is made to depend upon the closure of the preceding switch, but such closure does not depend on whether or not the circuit through the preceding switch is closed.

My invention has the further advantage that so called auxiliary or control circuit contacts are removed from the switches which control the main circuit connections.

Referring to the accompanying drawings, Figure 1 is a diagrammatic view illustrating my invention in connection with a simple non-reversing controller for a series-wound motor. Fig. 2 is a sectional view partly in elevation of a form of relay which is adapted for use in my invention.

On Fig. 1, S is a main switch connecting the motor and the controller to a source of current supply. A is the armature of the motor; F, the series field winding; R', R², and R³, sections of resistance adapted to be successively connected in the controlled circuit. These sections of resistance are gov-

erned respectively by the magnetically-operated switches S', S², and S³. When switch S' is closed, the resistance section R' is in series with the motor. When switch S² closes, the resistance section R² is placed in parallel with the resistance R', thus reducing the resistance in the motor circuit. When switch S³ closes the resistance section R³ is connected in parallel with resistance sections R' and R², thus further reducing the resistance, and when the switch S⁴ closes, the entire resistance is short circuited through the wire 4. The switches S' to S⁴ are provided with actuating windings C' to C⁴, respectively. M indicates a master switch of the drum type, by which the windings of the switches may be successively energized at the will of the operator by turning the drum of the switch so as to bring the contact strips n to n⁴ successively into contact with the stationary contact fingers m' to m⁴, respectively. The lower ends of each of the actuating windings of the magnetic switches are connected, respectively, to the contact fingers m' to m⁴ of the master switch. Each of the switches S' to S³ is provided with a series relay, the winding of which is included in the circuit closed by the switch. Each of these relays controls a pair of normally open contacts such that when current flows through the winding of the relay, these contacts are bridged and electrically connected together. It will be seen that the contacts of the relay L' are included in the circuit of the winding of the switch S'; the contacts of the relay L² are included in the circuit of the winding of the switch S², and the contacts of the relay L³ are included in the circuit of the winding of the switch S⁴.

The operation of this controller may be described as follows: Assuming that the main switch S is closed and that the drum of the master switch or controller is moved to bring the contacts n and n' into contact with the respective fingers m and m', the following circuit will be established: from the positive side of the switch S through the wire 1, the finger m of the master switch, the contact strips n and n', the contact finger m', the winding C' of the switch S', and the wires 5 and 3 to the negative side of the switch S. This completes the circuit through the winding of the switch S' which will then close. The circuit through the

motor is then completed as follows: from the positive side of the switch S through the wire 1, the contacts of the switch S', the winding of the relay L', the resistance section R', the wire 2, the field F and the armature A of the motor, and the wire 3 to the negative side of the switch S. Current thus flows through the winding of the relay L' which lifts its plunger and bridges the contacts a'.

When the master switch is moved into its next position, that is, when the strip n^2 is brought into contact with the finger m^2 , the winding C^2 of the switch S ^{2} is energized through the following path: from the positive side of the switch S, through the wire 1, the contact finger m , the contacts n , n' , and n^2 of the master switch, the finger m^2 the winding C^2 of the switch S ^{2} , the contacts a' of the relay L', and the wires 5 and 3 to the negative side of the switch S. The switch S ^{2} then closes, thus connecting the resistance section R ^{2} in parallel with the resistance section R', reducing the total resistance in the motor circuit. The circuit controlled by the switch S ^{2} includes the winding of the relay L ^{2} , and if this circuit is complete, that is to say, if there are no broken connections in the circuit controlled by the switch S ^{2} , the winding of the relay L ^{2} will be energized, and this relay will lift its plunger, thus closing the contacts a ^{2} which are in the circuit of the winding C ^{3} of the switch S ^{3} , which is the next switch to close. Similarly, by further rotation of the drum of the master switch, the switch S ^{3} is caused to close, thereby energizing the relay L ^{3} and putting the switch S ^{2} in a position to be closed, upon moving the master switch another step. When the switch S ^{4} closes, all of the resistance is short circuited, current then flowing through the motor as follows: from the positive side of the switch S, through the wire 1, the winding of the relay L ^{3} , the contacts of the switch S ^{4} , the wire 4, the field and the armature of the motor, and the wire 3 to the negative side of the switch S. The closure of the switch S ^{4} , therefore, in addition to short circuiting resistance sections R', R ^{2} , and R ^{3} also short circuits the windings of the relays L' and L ^{2} . These two relays, therefore, drop their plungers and the switches S ^{2} and S ^{3} automatically open. The switch S ^{4} , however, is maintained closed through the contacts of the relay L ^{3} since the motor current flows through the winding of this relay.

When it is desired to stop the motor, the drum of the master switch is turned back to its initial or off-position, which causes the switch S ^{4} to open and interrupt the motor circuit.

The windings of the relays L' to L ^{3} may be proportioned to carry the full current in the circuits controlled by their respective

switches, or they may be shunted so that any desired portion of the motor current will flow through the relay windings. I have indicated at K a shunt-around the winding of the relay L ^{2} . By properly proportioning the resistance of this shunt with respect to the resistance of the winding of the relay L ^{2} , any desired proportion of motor current may be caused to flow through the relay winding which is shown as surrounding the air-gap between the plunger and the plug.

While for simplicity I have shown my invention applied to the control of a non-reversing series-wound motor, it will be readily understood by those skilled in the art how the principle of my invention may be applied to reversing controllers or motor starters for shunt or compound wound motors and to other schemes of control where the successive closure of a series of switches is desirable or necessary.

By making the relays L' to L ^{3} of special form, the additional valuable result may be obtained of preventing successive closure of the switches until the current taken by the motor has dropped to a suitable value; in other words, succeeding switches will not close unless the motor current is below a predetermined value. By this means the current taken by the motor during acceleration may be made substantially constant and independent of the rapidity with which the operator moves his master controller. Where it is desirable to do so, the master controller, having a contact for each switch, may be replaced with a simple switch controlling the circuit of the switch S', the other switches closing automatically in predetermined order and only closing when the current taken by the motor is at a predetermined and proper value.

In Fig. 2 I have shown a form of relay adapted to the purposes of the relays L' to L ^{3} . In this relay b is a frame of magnetic material, the upper portion of which is provided with a central depending pole piece b ^{2} . K is the winding of the relay adapted to be connected as indicated in Fig. 1. b ^{4} is a core of magnetic material provided with a stem or extension b ^{10} also of magnetic material. This stem b ^{10} extends into the bore of a hollow adjustable plug b ^{3} of magnetic material. The upper end of the core b ^{4} is provided with an extension b ^{5} of brass or other non-magnetic material. This extension carries at its upper end a contact disk b ^{7} suitably insulated from the stem and adapted to bridge or connect the stationary contact points b ^{8} and b ^{9} . The shoulder b ^{6} serves to limit the downward motion of the core. This relay possesses the remarkable characteristic that, if a current at or below a predetermined value flows through the winding K, the core b ^{4} will be attracted to the boss b ^{2} , thereby causing the relay to close.

close its contacts b^8 and b^9 . If, however, the current through the winding K is above the said value, the lower face of the core b^4 will be more strongly attracted toward the face of the plug b^3 and the core will not rise until the current has been reduced to the said predetermined value. The value of current at which the relay will act to bridge its contacts may be adjusted in various ways, 10 but preferably by adjusting the air gap between the face of the plug b^3 and the lower face of the core b^4 , this being accomplished by screwing the plug b^3 in or out.

In the switch shown in Fig. 2, the magnetic flux appears to flow in a divided path in a part of the magnetic circuit, when the winding K is energized. The magnetic flux may be regarded as flowing from a point in the frame b , such as the pole b^2 , across the air-gap immediately below the pole b^2 and into the core b^4 . At the lower end of the core the flux divides into two paths, one path being through the core-extension b^{10} and into the plug b^3 and the lower end of the frame b , and the other path being from the lower end of the core b^4 , across the air-gap immediately below it and into the top of the plug b^3 , and thence through the plug to the lower end of the frame b . The flux flowing across the upper gap produces a force tending to raise the core b^4 , while the flux through the lower gap produces a force tending to prevent the core from being raised. If the winding is excited at a relatively low value, the larger part of the flux produced thereby will flow through the extension b^{10} , and since this flux passes horizontally into the frame, there is no tendency to prevent the plunger from moving upwardly, only a small part of the flux passing across the lower gap around the extension b^{10} . If the winding is excited at a high value the restricted area in the magnetic circuit through the extension b^{10} forces more flux to pass across the lower gap into the plug or pole b^3 , thereby increasing the force tending to prevent the upward movement of the core. The extension b^{10} is in the said applications of Canfield surrounded by a sleeve of non-magnetic material which serves as a guide for the core and prevents the core from sticking to the plug b^3 .

I disclaim the specific construction of this relay as part of this invention as the same is the invention of Harry R. Canfield and forms the subject matter of his applications for United States Patent, Serial Number 583,000, filed September 21, 1910, and Serial Number 604,331, filed January 23, 1911, 40 I do, however, claim the combination including this relay or its equivalent connected as illustrated in Fig. 1, or in modified ways which will readily suggest themselves to those skilled in the art.

65 Referring now to Fig. 1, with the relays

L' to L^3 constructed as shown in Fig. 2, assume that the operator moves his master switch suddenly to the full speed position, that is, until all of the contact strips n to n^4 are in contact with their respective fingers m to m^4 . A circuit is then completed through the winding C' of the switch S' , causing this switch to close. In closing the switch S' closes the main motor circuit through the winding of the first relay L' . 70 If the current which then flows is greater than that for which the relay is adjusted, the relay cannot lift its plunger and the winding C^2 of the switch S^2 remains de-energized. When, however, the motor current has fallen to a safe or predetermined value, the relay lifts its plunger, thus bridging the contacts a' and completing the circuit through the winding C^2 of the switch S^2 . The switch S^2 then closes, closing the 80 main or motor circuit through the winding of the relay L^2 which in a similar manner cannot permit the closure of the switch S^3 until the current has dropped to a predetermined value, if the current exceeds the 85 value for which the relay L^2 is set. The relay L^3 acts in a similar manner to prevent the closure of the switch S^4 until the current has dropped to a predetermined value.

With the described scheme of control, the 90 operator may control the number of switches closed by the position to which he moves the master switch, but he cannot, however, control the rate of progression of the closure of the switches since the rate is governed by 100 the motor current through the agency of the relays L' to L^3 ; nor can he cause the switches to close out of their predetermined order, which is also determined by the relays L' to L^3 . It will be understood that, if open 10 circuits exist in any of the resistance sections R' , R^2 , and R^3 or their connections, the successive closure of the switches will be interrupted when this point is reached in the acceleration and the motor cannot be 110 brought up to full speed until the trouble is repaired. For instance, if there should be an open connection in the circuit of the resistance section R^2 , when the switch S^2 closes, no current could flow through the 115 winding of the relay L^2 ; consequently, the winding of the switch S^3 cannot be energized until the trouble is remedied. Similarly, if there is an open circuit in the connection including the resistance section R^3 , 120 no current could flow through the winding of the relay L^3 even though the switch S^3 is closed; consequently, the switch S^4 could not be closed.

125 I claim—

1. In an electric controller, the combination of a series of magnetically operated switches to be successively closed, the circuits of the actuating windings of the said magnetically operated switches being in 130

- shunt with or derived from the controlled circuit, and means for preventing further successive closure of said switches in case any one of said switches when closed fails to establish a circuit through its main contacts.
2. In combination, a series of magnetic switches each adapted to close a pair of main contacts, each of said switches having an actuating winding independent of the circuit controlled by said main contacts, and means for preventing the closure of a succeeding switch unless current flows through the main contacts of the switch which precedes in operation.
3. The combination, in an electric controller, of a series of switches each having main contacts and an actuating winding, relays associated with certain of said switches and having normally open contacts in the circuit of the winding of the switch next to close, said relays having windings arranged to be successively connected in the controlled circuit by the closure of the main contacts of the said switches and movable contacts on said relays actuated by the said windings to close the said normally open contacts.
4. In an electric controller, a series of magnetically-operated switches to be successively closed, means for inforcing said successive closure, said means comprising normally open contacts in the circuit of the winding of each of said switches except the first to operate, a relay for each of said normally open contacts, said relay being arranged to connect said contacts when its winding is energized, the winding of the relay controlling the contacts in the circuit of the winding of the second switch being included in the controlled circuit by the closure of the second switch.
5. In an electric controller, a series of consecutively-acting magnetic switches, a relay adapted when energized to close the circuit through the actuating winding of each of said switches, except the first to close, each of said relays being included in the controlled circuit by the switch which precedes in operation.
6. In an electric controller, a series of consecutively-acting magnetic switches, a relay arranged to control the circuit through the actuating winding of each of said switches, except the first to close, each of said relays being included in the controlled circuit by the switch which precedes in operation, said relays having normally open contacts being constructed to close their contacts only when the current through their windings is less than a predetermined amount.

7. The combination, in an electric controller, of a series of switches each having main contacts and an actuating winding, a relay associated with certain of said switches and having contacts in the circuit of the winding of the switch next to close, said relays having windings arranged to be successively connected in the controlled circuit by the closure of the main contacts of said switches, each of said relays having normally open contacts being so constructed as to close its contacts only when the current through its winding is below a predetermined value.

8. The combination, in an electric controller, of a series of switches, each having main contacts and an actuating winding, relays associated with certain of said switches and having contacts in the circuit of the winding of the switch next to close, said relays having windings arranged to be successively connected in the controlled circuit by the closure of the main contacts of said switches, each of said relays having normally open contacts being so constructed as to close its contacts only when the current through its winding is below a predetermined value, and means for adjusting the said relays as to the current value at which they will close their contacts.

9. In an electric controller, a series of magnetically operated switches to be successively closed, means for inforcing their successive closure, said means comprising normally open contacts in the circuit of the winding of each of said switches except the first to operate, a relay for each of said normally open contacts, said relay being arranged to connect said contacts when its winding is energized by a current below a predetermined value, the winding of the relay controlling the contacts in the circuit of the winding of the second switch being included in the controlled circuit by the closure of the first switch, the winding of the relay controlling the circuit of the winding of the third switch being included in the controlled circuit by the closure of the second switch, and so on.

10. In an electric controller, a series of magnetically operated switches to be successively closed, means for inforcing their successive closure, said means comprising normally open contacts in the circuit of the winding of each of said switches except the first to operate, a relay for each of said normally open contacts, said relay being arranged to connect said contacts when its winding is energized by a current below a predetermined value, the winding of the relay controlling the contacts in the circuit of the winding of the second switch being included in the controlled circuit by the closure of the first switch, the winding of the relay controlling the circuit of the winding of the third switch being included in the controlled circuit by the closure of the second switch, and so on.

of the third switch being included in the controlled circuit by the closure of the second switch, and means for adjusting said relays as to the current value at which they will close their contacts.

11. In an electric controller, a series of consecutively acting magnetic switches, a relay adapted when energized to close the circuit through the actuating winding of each of said switches except the first to close, each of said relays being included in the controlled circuit by the switch which precedes in operation, each of said relays being so constructed as to close its contacts only when the current through its winding is below a predetermined value.

12. In an electric controller, a series of consecutively acting magnetic switches, a re-

lay adapted when energized to close the circuit through the actuating winding of each of said switches except the first to close, each of said relays being included in the controlled circuit by the switch which precedes in operation, each of said relays being so constructed as to close its contacts only when the current through its winding is below a predetermined value, and means for adjusting said relays as to the current value at which they will close their contacts.

Signed at Cleveland, Ohio, this 19th day 30 of September, 1910.

ARTHUR C. EASTWOOD.
